CLARK W. GOULD, OF VERNONIA, OREGON, ASSIGNOR TO WESTERN BLOWER COMPANY,
OF SEATTLE, WASHINGTON.

DRY KILN.

Application filed September 28, 1925. Serial No. 58,719.

This invention relates to improvements in drying kilns for various materials but particularly for the drying of lumber; the principal object of the invention being to 5 provide a kiln embodying means whereby a forced circulation of the drying medium, that is, heated air, may be effected with a high degree of efficiency and economy.

More particularly the invention resides in 10 the details of construction and relationship of the air heating and air circulating means to a novel arrangement of baffles and deflectors whereby the air is caused to circulate in such manner as to effect a uniform drying of the material within the kiln in a 15 minimum length of time.

Other objects of the invention reside in 20 the various details of construction and combination of parts as will hereinafter be described.

In accomplishing these objects of the invention, I have provided the improved details of construction, the preferred forms of which are illustrated in the accompanying 25 drawings, wherein—

Figure 1 is a vertical, transverse section of a drying kiln embodied by the present invention.

Figure 2 is a vertical section taken longitudinally of the kiln on the line 2—2 in 30 Figure 3.

Figure 3 is a horizontal section of the kiln taken substantially on the line 3—3 in Figure 2.

Figure 4 is a perspective view of a part 35 of the air circulating mechanism, showing the arrangement of baffles.

Figure 5 is a transverse sectional detail of a modified construction showing the lateral walls of the air collector extended to 40 the floor.

Figure 6 is a fragmental, side view of an alternative construction wherein the baffles are arranged in vertical planes instead of 45 inclined.

Referring more in detail to the several views of the drawings—

1 and 2 designate opposite side walls of 50 the kiln, 3 the floor, 4 the top or roof, and 5 and 6 the opposite end walls, all of which are united to form a closed chamber suitable for the drying of lumber or other material therein. The end walls are made with suitable openings 7 through which the ma-

terial to be dried may be moved into or 55 from the kiln and doors 8 are provided whereby the openings may be closed.

Extending lengthwise of the kiln and through the openings 7 are parallel rails 9 forming a track on which wheeled cars or 60 trucks 10, as shown in Figure 1, may travel and on which the lumber to be dried may be stacked and moved into and from the kiln. The rails 9 are supported at regular intervals by I-beams 11 that extend 65 transversely between the side walls of the kiln and at such elevation above the floor as to provide sufficient space below them for the air heating means and mechanism provided for the promoting of a circulation 70 of the air through and about the material being dried.

The trucks 10 may be of any desirable character suitable for this work upon which the boards to be dried are stacked in edge-wise form so as to provide at frequent intervals, longitudinally continuous, vertical slits or passages 12 through which the drying air may pass. The side walls of the truck and stack of lumber are close to the 80 side walls of the kiln and provide passages 13 through which the heated air may pass upwardly and then over the top of the load and then downwardly through the slits 12.

The air heating means which I prefer and 85 which is herein illustrated is of the return bend type and consists of a plurality of steam pipes 14 that extend, in vertically spaced relation, longitudinally of the kiln along the opposite side walls below the level of the 90 track and these are supplied with steam or other heating medium desired from a source outside the kiln through the feed pipes 15.

The means provided for promoting and 95 properly directing the air circulation consists of baffle plates 17 and 18 which extend substantially the length of the kiln and which are relatively convergent, as shown best in Figure 1, the upper edges of these baffles terminating just below the level of the 100 bottom of the truck 10 and their transverse extent preferably being equal to the width of the trucks so that they serve as a collector of the air currents coming downwardly from the slits or passages 12 in the 105 lumber stacked on the truck. The distance between the lower edges of the convergent baffles should be at least equal to the sum

of the widths of all the slits 12 so as to accommodate all the air that comes through them.

The baffle plates 17 and 18 constitute, as shown best in Figure 1 and Figure 4, a longitudinally extended collector to a longitudinally co-extensive compartment 21 that is defined by two vertical, spaced apart lateral walls 22 and 23, the lower edges of which, as shown in Figures 1 and 2, terminate at sufficient distance above the floor as to permit an easy exhaust of the air from the collector toward the opposite sides of the kiln, but they may, if desired, be extended to the floor and the air exhausted through the side openings, presently described.

At spaced intervals throughout the length of the compartment 21 are transverse partitions or walls 25 with circular openings 26 therein within which suction fans 27 operate; the fans being fixed to a shaft 28 that extends longitudinally of the kiln centrally of the compartment 21 and which is rotatably mounted in journals 29 on hangers or brackets 30 suspended from certain of the I-beams 10. The shaft may be rotated by any suitable mechanism such as a motor 30, shown in Figure 3, which preferably is located externally of the kiln.

At corresponding sides of each of the partitions 25 in spaced relation thereto and to the fans 27, are baffle plates 34 that extend transversely of the compartment 21 between the walls 22 and 23. These baffles, as shown in Figures 1 to 4, are inclined downwardly away from the fans. The side walls 22 and 23 are cut away between the baffles and partition walls 25 so as to provide lateral openings 35 and the top of the compartment 21 between the upper edges of the baffles 34 and partition walls 25 are closed by horizontal plates 36 so that air blown by the fans against the baffles will not be diverted upwardly.

Within the closed portion of the compartment 21 about midway between the fans and baffles 34 are correspondingly inclined baffle plates 40 extended between the walls 22 and 23 across the upper half of the compartment. These latter baffles serve with the baffles 34 to direct the air after it moves downwardly through the load of lumber and into the collector, to the fans which operate to discharge it through the lateral openings 35 to the heating pipes.

In the modified construction, shown in Figure 6, the baffles 40 and walls 34 are arranged in vertical planes for, in some instances, this is more desirable.

The movement of heated air upwardly along the sides of the kiln in the passages 13 may be accelerated by the placing of pipes 41 longitudinally of the kiln adjacent the side walls below the level of the truck and to provide these pipes at closely spaced in-

tervals with orifices 41' through which steam may be forcibly discharged in an upward direction. Pipes 42 may likewise be located adjacent the top of the kiln to discharge jets of steam downwardly to accelerate circulation in a reverse direction.

Assuming that the kiln is so constructed, its operation would be as follows: Trucks 10 would first be loaded with lumber to be dried, stacked in edgewise relation to provide the vertical slits 12 through the load as shown in Figure 1, and the trucks moved into the kiln and the latter closed.

As the air is heated, incidental to the application of steam to the pipes 14 of the heating system, it rises along the side walls of the kiln to the top and then rolls inwardly over the top of the load and is then drawn by suction downwardly through the slits 12 in the load and into the collector defined by the convergent baffles 17 and 18 and compartment 21. The operation of the fans draws the air from the collector into the compartment 21 where it is deflected by the inclined baffles 34 and 40 to the fans and is discharged thereby through the openings 26 in the partition walls 25 and against the under sides of the baffles 34 and is expelled laterally through the openings 35 to the pipes of the heating system for reheating and a continuous repetition of the operation. At the start, the circulation may be augmented by the discharge of steam from the pipes 40 as before stated.

The important feature of the present system resides in the relation of the baffle plates to the load and to each other and their continuing walls 22 and 23 which, with the side walls of the truck 10, serve to separate the upwardly moving heated air from the downwardly moving air that is saturated with moisture absorbed from the material being dried.

It is to be understood that while I have described the operation for the movement of air in a downward direction through the load, it may, if desired, be reversed by a reversal of the direction of operation of the fans.

Having thus described my invention, what I claim as new therein and desire to secure by Letters-Patent, is:

1. A dry kiln comprising a chamber, and truck supporting tracks therein, in combination with baffle plates extending below said tracks substantially the length of the chamber and spaced from the sides of the chamber, respectively, and from each other, and means for producing heated air circulation within the chamber between the baffle plates and at the respective sides thereof.

2. A dry kiln comprising a chamber, and truck supporting tracks therein, in combination with mutually converging baffle plates extending below said tracks substantially

the length of the chamber and spaced from the sides of the chamber, respectively, and from each other, and means for producing heated air circulation within the chamber 5 between the baffle plates and at the respective sides thereof.

3. A dry kiln comprising a chamber, and truck supporting tracks therein, in combination with baffle plates extending below said 10 tracks substantially the length of the chamber and spaced from the sides of the chamber, respectively, and from each other, lateral walls defining a compartment open for air circulation below the baffle plates, and 15 heating means disposed within the chamber upon opposite sides of said compartment.

4. A dry kiln comprising a chamber, and truck supporting tracks therein, in combination with baffle plates extending below said 20 tracks substantially the length of the chamber and spaced from the sides of the chamber, respectively, and from each other, lateral walls defining a compartment open for air circulation below the baffle plates, and 25 heating means consisting of return bend heater system disposed within the chamber upon opposite sides of said compartment.

5. A dry kiln comprising a chamber, and truck-supporting tracks therein, in combination 30 with baffle plates extending below said tracks substantially the length of the chamber and spaced from the sides of the chamber, respectively, and from each other, lateral walls defining a compartment open for 35 air circulation below the baffle plates, heating means disposed within the chamber upon opposite sides of said compartment, and means for aiding air circulation disposed within said compartment.

40 6. A dry kiln comprising a chamber, and truck-supporting tracks therein, in combination with heating means disposed within the chamber below the tracks and on opposite sides of the chamber, in combination with 45 means disposed medially within the chamber for collecting the circulatory medium of air circulation promoted by said heating means and for diverting said medium towards opposite sides of the chamber.

50 7. A dry kiln comprising a chamber, and truck-supporting tracks therein, in combination with baffle plates extending below said tracks substantially the length of the chamber and spaced from the sides of the chamber, respectively, and from each other, means 55 for producing heated air circulation within the chamber between the baffle plates and at the respective sides thereof, and upwardly discharging accelerator pipes located in operative relationship to the spaces between the baffle plates, respectively, and the adjacent walls of the chamber.

60 8. A dry kiln comprising a chamber, and truck-supporting tracks therein, in combination 65 with baffle plates extending below said

tracks substantially the length of the chamber and spaced from the sides of the chamber, respectively, and from each other, lateral walls defining a compartment open for air circulation below the baffle plates, heating means disposed within the chamber upon opposite sides of said compartment, and means for aiding air circulation disposed within said compartment, said means last named consisting of rotative fans mounted 70 in said compartment.

9. A dry kiln comprising a chamber, and truck-supporting tracks therein, in combination with baffle plates extending below said 75 tracks substantially the length of the chamber and spaced from the sides of the chamber, respectively, and from each other, lateral walls defining a compartment open for air circulation below the baffle plates, heating means disposed within the chamber upon 80 opposite sides of said compartment, and means for aiding air circulation disposed within said compartment, said means last named consisting of rotative fans mounted 85 in said compartment, said compartment being subdivided for the operative accommodation of each fan.

10. The combination within a chamber of truck-supporting tracks and trucks united 90 in pairs by cross-beams with an edgewise piled load of lumber on the cross-beams disposed so as to provide vertical spaces between the load and the opposite side walls of the chamber for air circulating in one direction, and vertical slits through the body 100 of the load for air circulation in direction opposite to that of the air circulation first named, means for producing heated air circulation through said spaces and slits, and means for collecting the air discharged from 105 the complement of slits and distributing in circulation to the spaces aforesaid, respectively.

11. A dry kiln comprising a chamber, and truck-supporting tracks therein, in combination 110 with baffle plates extending below said tracks substantially the length of the chamber and spaced from the sides of the chamber, respectively, and from each other, lateral walls defining a compartment open for 115 air circulation below the baffle plates, heating means disposed within the chamber upon opposite sides of said compartment, and means for aiding air circulation disposed within said compartment, said means last named consisting of rotative reversible fans mounted in said compartment, said compartment being subdivided for the operative accommodation of each fan, and accelerator and reverse accelerator pipes having, respectively, oppositely discharging jet orifices and being alternately operative to suit 120 the direction of rotation of the fans.

12. A dry kiln comprising a chamber, and truck-supporting tracks therein, in combi- 125

1 nation with baffle plates extending below said tracks substantially the length of the chamber and spaced from the sides of the chamber, respectively, and from each other, 5 lateral walls defining a compartment open for air circulation below the baffle plates, transverse vertical partitions subdividing said compartment having openings therein, a rotative, reversible shaft extending longitudinally of the compartment through 10 said openings, fans on said shaft within said openings, inclined baffle plates closing off said compartment at corresponding sides of the partition walls, and said lateral walls 15 being cut away between said partition walls and said inclined baffles thereby providing lateral openings for the exhaust of air, and heating means at opposite sides of said compartment.

20. 13. A dry kiln comprising a chamber, and

truck-supporting tracks therein, in combination with baffle plates extending below said tracks substantially the length of the chamber and spaced from the sides of the chamber, respectively, and from each other, lateral walls defining a compartment open for air circulation below the baffle plates, said compartment having openings in its opposite sides for the discharge of air therefrom, transverse vertical partitions subdividing said compartment and having openings therein, fans operable in said openings for the withdrawing of air from the subdivisions of said compartment and baffles arranged transversely of the compartment for deflecting air from the fans, through said lateral openings.

Signed at Vernonia, Columbia County, Oregon, this 1st day of September, 1925.
